United States Patent Office

Des. 207,878
Patented June 6, 1967

207,878

STAND UP PIANO

Odie Bradford, Memphis, Tenn., assignor to Aeolian Corporation, Bronx, N.Y., a corporation of New York

Filed July 27, 1965, Ser. No. 86,302

Term of patent 3½ years

(Cl. D56—9)

FIG. 1

FIG. 2

FIG. 3

FIG. 4

FIG. 1 is a top plan view of a stand up piano showing my new design;

FIG. 2 is a front elevational view;

FIG. 3 is a right end elevational view, the left end being substantially a mirror image thereof; and

FIG. 4 is a front, top and left side perspective view thereof.

The back, not shown, is a substantially flat, unornamented surface.

I claim:

The ornamental design for a stand up piano, substantially as shown and described.
